(57) **CLAIM**

The ornamental design for "stripe visor," as shown and described.

DESCRIPTION

FIG. 1 is a perspective view of "stripe visor" showing my new design

FIG. 2 is a top plan view of FIG. 1

FIG. 3 is a front elevational view of FIG. 1

FIG. 4 is a right side elevational view of FIG. 1, the left side is a mirror image.

FIG. 5 is a rear elevational view of FIG. 1; and,

FIG. 6 is a bottom plan view of FIG. 1.

The dashed lines showing a headwear crown in all views are for illustrative purposes only and form no part of the claimed design.

The broken lines shown on the visor represent stitching.
